MULTI-LEAF TORSION SPRING FOR CLOSING A BREECHBLOCK

Marvin J. Engel, Albany, Owen D. Hoopes, Latham, and John B. Sillery, Albany, N. Y., assignors to the United States of America as represented by the Secretary of the Army

Application December 21, 1954, Serial No. 476,861

3 Claims. (Cl. 89—17)

The invention described herein may be manufactured and used by or for the Government for governmental purposes without the payment of any royalty thereon.

This invention relates to breech mechanisms for firearms and more particularly to the spring means for closing the breechblock member thereof.

In designing those guns which are to be mounted in combat vehicles such as tanks, the limited space available inside of the turrets necessitates a continuing effort to reduce the size of the weapons without sacrificing fire power.

One of the most space consuming of the components of a cannon located within a turret is the breech mechanism which requires cooperating mechanical linkages, springs and arrangements of components to perform its function of opening the chamber of the gun tube for the extraction of a spent cartridge case and the loading of a live round and of closing the chamber for the firing of the round.

In virtually all cannons used in tanks, the breechblocks are opened by using the energy of gun recoil or counter-recoil to rotate a crank which lowers the breechblock to an open position and at the same time ejects the spent cartridge case and energizes a spring device linked to the breechblock. The spring retains the stored energy until the breechblock is released for closing by a newly chambered round which trips the extractors holding the breechblock in open position, at which time the automatically released energy of the spring closes the breechblock to make the gun ready for fire.

Many types of springs have been used for this purpose. The one most commonly used is a straight helical compression spring, but this arrangement utilizes a large amount of space because of the separate housing required for the spring and the cooperating linkages located along side the breech. Clock springs have also been used, but again the space ratio of spring to breech is on the high side. Torsion helical springs of both square and round highly stressed wire have been used successfully for reducing the amount of occupying space per unit of energy, but the space gain is accomplished through the use of critical material which in applications for cannons of larger caliber than 75 mm. is prohibitive. The use of lower strength wire means that working stresses must be lowered, consequently the spring increases in size and its advantage in compactness becomes lessened.

A solid bar of either round or rectangular cross-section enables a large amount of energy to be stored in a small space when subject to angular movement, but the angular movement allowable before plastic flow starts is much too small to effectively close the breech of a gun.

It is the object of this invention to provide for the breech mechanism of a firearm a torsional spring device for closing the breechblock unit which has the advantage of the space gain provided by a torsional bar spring, yet may be operated through an angular movement sufficient to close the breechblock without being over-stressed, and

2

the further advantage of being formed from readily available, non-critical material.

It is another object of this invention to provide for the breech mechanism of firearms a space saving spring for closing the breechblock of a firearm which is comprised of a plurality of thin leaves stacked to form a torsional spring of rectangular cross-section. Thus, each leaf acts as an independent torsion bar, subject to torsional load about its longitudinal axis of symmetry, and by this distribution of load the stress in the torsional spring for any given angular twist is reduced.

It is a further object of this invention to provide for the breech mechanism of firearms a torsional bar spring for closing the breechblock which is adjustable to any desired torsional moment.

It is a still further object of this invention to provide for the breech mechanism of firearms a spring for closing the breechblock which is mountable within the operating shaft and so does not occupy any space in addition to the designed configuration of the operating components and which provides a more nearly symmetrical breech mechanism.

The specific nature of the invention as well as other objects and advantages thereof will clearly appear from a description of a preferred embodiment as shown in the accompanying drawings in which:

Fig. 1 is a view showing the rear end of a cannon;

Fig. 2 is an enlarged view taken along line 2—2 of Fig. 1;

Fig. 3 is an enlarged rear end view of the cannon partially broken away to show the angular relationship of the breechblock closing spring when the breechblock is in open position;

Fig. 4 is an exploded perspective view of the breechblock operating mechanism;

Fig. 5 is an enlarged view taken along line 5—5 of Fig. 1;

Fig. 6 is an enlarged side view showing the operating crank at point of engagement with the ejector cam during counterrecoil of the cannon;

Fig. 7 is a view taken along line 7—7 of Fig. 6;

Fig. 8 is an enlarged side view showing the breechblock operated to open position by the engagement of the operating crank with the ejector cam during counterrecoil of the cannon;

Fig. 9 is a view taken along line 9—9 of Fig. 8;

Fig. 10 is an enlarged fragmentary view showing the ejector cam in normal position in relationship to the gun mount;

Fig. 11 is a view similar to Fig. 10 but showing the ejector cam biased inwardly by the operating crank during recoil of the cannon;

Fig. 12 is an enlarged perspective view of the ejector cam; and

Fig. 13 is an enlarged perspective exploded view of the adjusting device.

Shown in the figures is a breech mechanism of a slide block cannon including a breech ring 12 and a breechblock 14 mounted for slidable movement therein on ways (not shown). Depending from the bottom of breech ring 12 is a left lug 18 and a right lug 20 spaced laterally therefrom. Right lug 20 is provided with a bore 22 which is counterbored, as noted at 23, to rotatably receive an adjustor member 24 having a cylindrical portion 26 received within such counterbore and a larger diameter portion 28 which engages the right side of such lug. Extending through adjustor member 24, symmetrical with the axis thereof, is a rectangular opening 32, which is chamfered, as noted at 33, at the end inside of portion 26. A set screw 34 is threadably mounted through right lug 20 to be received by an annular groove 36 around portion 26 whereby adjustor member 24 is rotatable in

counterbore 23 but is restrained from lateral displacement. A plunger 27 is slidably mounted in breech ring 12 in back of portion 28 and is biased against such portion by a coil spring 30. Plunger 27 is receivable by a cooperating notch 31 in portion 28 which notch is provided with a plurality of step portions 35 as best shown in Fig. 13 to provide the means for selectively adjusting the rotatable position of adjustor member 24.

Left lug 18 is bored, as noted at 37, to receive a cylindrical shaft 38 having a bearing portion 42 rotatably received by such bore and a reduced diameter axle portion 40 which extends from such bearing portion to be rotatably received by bore 22. The end of bearing portion 42 adjacent axle portion 40 is cut back to form a semi-annular recess 46 for receiving a key portion as hereinafter noted. Shaft 38 extends beyond left lug 18 and provided on such extending portion is an operating crank 48 having an integral hub 50 which is spaced from the adjacent side of left lug 18 by a cylindrical flange portion 52. A set screw 54 mounted threadably through left lug 18 is received by an annular groove 56 around bearing portion 42 to secure shaft 38 against lateral displacement while being rotatable.

Extending radially from hub 50 are a protruding portion 58 and an integral arm 60. A stud 62 extends laterally outward from arm 60 to be engageable during counter-recoil of breech ring 12 with a conventional ejector cam 64 mounted on a gun mount 66 for rotation of shaft 38. Ejector cam 64, of conventional design and operation, is spring-biased outwardly from mount 66 to an operating crank engaging position by a cooperating spring 65, whereby stud 62, during the recoil portion of the operating cycle, engageably actuates such cam inwardly to ride thereover. An operating handle 68 is rotatably mounted on flange portion 52 and is provided with a plunger 70 receivable by a radial slot 72 in protruding portion 58 to engage such handle to shaft 38 when manual operation thereof is desired.

Mounted on axle portion 40 is a breechblock crank 74 having a hub portion 76, which is bored as noted at 78 to receive such axle portion, and an arcuate arm portion 80 extending therefrom. A semiannular key portion 82 projects from hub portion 76 to mate with recess 46 whereby breechblock crank 74 is engaged for unitary rotation with shaft 38 and is arranged to extend from shaft 38 in approximately the same direction as operating crank 48. A hollow cylindrical spacer 84 is mounted on axle portion 40 between right lug 20 and breechblock crank 74 for maintaining key portion 82 thereon in recess 46. Extending laterally through the free end of arm 80 is a cross-head pivot pin 86 which is mounted therein to extend beyond both sides of such arm, as noted at 88.

Rotatably mounted on extending portions 88 of pin 86 is a pair of cylindrical cross-heads 90 which are slidably received in a pair of diagonal grooves 92 in breechblock 14. Whereby, rotation of shaft 38 causes breechblock crank 74 to cammingly raise such breechblock to a close position or to lower such breechblock to an open position.

Extending into shaft 38 from the end of axle portion 40 thereof is an axial hole 94 which is terminated by a rectangular mouth portion 96 symmetrical therewith. Extending through mouth portion 96 and opening 32 in adjustor member 24 is a torsional spring 98 of rectangular cross-section which is comprised of a plurality of stacked spring leaves 99. Mouth portion 96 and opening 32 are so dimensioned that the walls thereof adjacent the top and bottom ones of the stacked spring leaves 99 are in close engagement therewith with clearances provided between the edges of such spring leaves and the walls of such mouth portion and opening. A driving pin 100 is mounted diametrically through base portion 50 of operating crank 48 to pass through aligned cylindrical holes 102 provided in one end of leaves 99. A retaining pin 104 is slidably mounted diametrically through portion 26 of adjustor member 24 to pass through aligned elongated holes 106 in the opposite ends of leaves 99. Engagement of the ends of pin 104 with the wall of counterbore 23 secures such pin against displacement.

Rotation of operating crank 48 by the engagement of stud 62 with ejector cam 64 rotates shaft 38 to lower breechblock 14 to open position and at the same time twists torsional spring 98 to store energy therein for closing such breechblock. The elongations of holes 106 permit longitudinal displacement of leaves 99 when twisted and the clearances between the edges of spring leaves 99 and the adjacent walls of mouth portion 96 and opening 32 permit angular displacement of such leaves about pin 100 and retaining pin 104, as best noted in Fig. 9 due to the helix angle produced when such spring leaves are twisted. Thus, there is imparted to spring 98 as near a true torsional load as is possible. Four equally spaced holes 108 are provided in the outer face of adjustor member 24 to permit the use of a conventional spanner wrench for turning such adjustor member to adjust the preload of torsional bar spring 98 and thereby assure the closing of breechblock 14 when released from open position. Such adjustment is possible through the cooperation of plunger 27 with the step portions 35 of notch 31 which are arranged to become progressively of lesser depth in the direction which spring 98 applies force to shaft 38 for raising breechblock 14 to blocking position. To increase the preload in spring 98, adjustor member 24 is rotated by a spanner in the direction of the applied force of such spring until the next one of the step portions 35 aligns with plunger 27 which, through the bias of spring 30, will automatically seat itself therein. To "back-off" the preload, plunger 27 is depressed a sufficient lateral distance to clear the undesired one of the step portions 35 whereby the preload in spring 98 will automatically rotate adjustor member 24 to engage the next shallower one of the step portions 35 with such plunger.

Operation

When the cannon is fired the recoiling components thereof, including breech ring 12 and breechblock 14, move rearwardly in gun mount 66 with stud 62 of operating crank 48 engaging ejector cam 64 which is cammingly pivoted thereby against the bias of spring 65 to permit such stud to ride over such cam. During the ensuing counterrecoil of breech ring 12, stud 62 engages the now outwardly projecting rear end of ejector cam 64 whereby operating crank 48 is turned, rotating shaft 38 which is integral therewith.

Rotation of shaft 38 causes simultaneous rotation of breechblock crank 74 which is engaged for simultaneous rotation therewith by the engagement of key portion 82 of such breechblock crank with recess 46 in bearing portion 42 of such shaft. Whereby, cross-heads 90 are moved along grooves 92 in breechblock 14 during rotation of breechblock crank 74 to cammingly lower such breechblock in breech ring 12 to open position. When breechblock 14 is in open position, a pair of conventionally operating extractors (not shown), which have expelled the spent cartridge case from the cannon during the opening of such breechblock, lock such breechblock in the open position.

During rotation of shaft 38, the end of spring 98 received by mouth portion 96 of such shaft is turned, but as the opposite end of the spring is held against turning by opening 32 in adjustor member 24 such spring and the spring leaves 99 thereof are twisted to store energy therein. This energy stored in spring 98 is utilized to rotate shaft 38 in the opposite direction and thereby raise breechblock 14 to close position when the extractors (not shown) are tripped by a fresh round being chambered in the cannon.

Thus, it is readily apparent that there is herein provided a simple and compact spring device for closing the breech-block of cannons which does not occupy any space therein in addition to the designed configuration of the operating

components and which is easily adjusted to any desired torsional movement.

Although a particular embodiment of the invention has been described in detail herein, it is evident that many variations may be devised within the spirit and scope thereof and the following claims are intended to include such variations.

We claim:

1. In a cannon having a breech ring with a breechblock mounted therein for slidable movement between an open position and a closed position, a shaft mounted for rotatable movement in the breech ring, crank means mounted to said shaft for camming cooperation with the breechblock for actuation thereof between the open and close positions, an adjustor member mounted for rotatable movement in the breech ring, said adjustor member being axially aligned with said shaft and adjacent one end thereof, said shaft being provided with a bore introduced into the end thereof adjacent said adjustor member, said bore being terminated by a rectangular mouth portion, said adjustor member being provided with a rectangular opening similar to said mouth portion, a torsional spring of rectangular cross-section mounted in said bore with the ends thereof being received by said mouth portion and said opening, a drive pin mounted through said shaft

and a mating circular hole through said spring for anchoring said spring to said shaft, a retaining pin mounted through said adjustor member and an elongated hole in said spring, said elongated hole providing for linear displacement of said spring when twisted, and a plunger resiliently mounted in said breech ring for cooperation with a stepped recess in said adjustor member to selectively position said adjustor member for adjustably pre-loading said spring to assure actuation of the breechblock thereby to the close position.

2. The combination as defined in claim 1 wherein said torsional spring comprises a plurality of stacked spring leaves.

3. The combination as defined in claim 1 with clearances provided in said mouth portion and said opening for the angular displacement of said spring leaves when twisted.
